UNITED STATES PATENT OFFICE

HENRY M. QUACKENBUSH, OF HERKIMER, NEW YORK, ASSIGNOR TO
MANNING A. DEIMEL, OF SAME PLACE.

SMOKE-CONSUMING APPARATUS.

SPECIFICATION forming part of Letters Patent No. 609,628, dated August 23, 1898.

Application filed March 31, 1898. Serial No. 675,958. (No model.)

To all whom it may concern:

Be it known that I, HENRY M. QUACKENBUSH, a citizen of the United States, residing at Herkimer, in the county of Herkimer and 5 State of New York, have invented certain new and useful Improvements in Smoke-Consuming Apparatus, of which the following is a specification.

My present invention pertains to improvements in smoke-consumers for furnaces, the advantages and construction of which will be hereinafter set forth, reference being had to the annexed drawings, wherein—

Figure 1 is a front elevation of the apparatus; Fig. 2, an enlarged detail view of a certain portion of the apparatus, partly in section, the section of the lower part of the plunger or piston-head being taken on the line $x-x$ of Fig. 3; Fig. 3, a top plan view of 15 the plunger or piston-head; Fig. 4, a vertical sectional view on the line $y-y$ of Fig. 1; Fig. 5, a horizontal sectional view of one of the inlet-chambers; Fig. 6, a perspective view of the deflecting and controlling slides, and Figs. 20 7 and 8 views illustrating modifications.

The object of the invention is to provide suitable and simple means for automatically controlling the admission of steam and air into the furnace above the fire when the furnace-door is opened and also for a period after the door is closed.

To this end the invention consists in providing suitable devices which when the furnace-door is opened are automatically and 35 without further thought or action upon the part of the attendant thrown into action, permitting a determinate quantity of steam and air to be introduced above the fire so long as the door remains open and for a certain period 40 thereafter.

In the drawings Figs. 1 and 2, A denotes the front wall or face of the furnace, and B the fire-doors, which open into the fire-chamber beneath the boiler C. Above the doors 45 B there are formed in the wall two openings D, preferably oblong in form and communicating with the fire-chamber at a point slightly below the level of the boiler. These openings are usually lined with an iron box or casing E. Within each of said openings there

are mounted two slides F and G, Figs. 4, 5, and 6, the side walls of the former slide being beveled or inclined at their forward ends, forming inclined faces a. The upper slide G is provided with a forwardly-extending lip or 55 deflector H, which is inclined downwardly, as indicated in Figs. 4 and 5, the angle of inclination preferably conforming to the bevel of the face a. Each of the slides is provided with a rearwardly-extending handle I, having upturned ends designed, primarily, to afford an easy grip and also to act as a stop to engage the lining or box E and prevent the slides from being projected too far inward.

It is manifest that the lower slide under 65 certain constructions may be dispensed with and the upper deflecting-slide mounted substantially as shown in Fig. 7. Upon reference to said figure it will be noted that a rib G' extends out from the casing E, upon which the lower edge of the slide rests, while upon the opposite side the casing is formed with a groove, into which extends the inturned or horizontal edge of the slide. It is manifest that either of these constructions may be 70 employed on both sides or that the upper part of the casing could be enlarged slightly to receive the slide, the edges thereof resting upon the protruding edges of the smaller lower portion. With any of these constructions the lower slide of course will be absent, and the deflector H will practically close the air-inlet when the slide is drawn back. So, too, the beveled faces a can be dispensed with and the deflector H made narrow enough to 75 pass in between the upstanding edges of the lower slide.

J denotes a pipe leading from the boiler or other suitable steam-supply, the pipe passing across the front of the furnace in line with 80 the openings D, suitable laterals K being connected thereto and extending into said openings. A manifold L is connected to each of said laterals and a series of spraying nozzles or jets M extend out from said manifold. 85

A valve N is located in pipe J, its stem being connected to a lever O, which is pivoted to a link P, secured to a bracket Q, the bracket extending out from the furnace-front.

R denotes a cylinder, which, as shown, is 90

also carried by bracket Q. The interior diameter of the cylinder is the same throughout with the exception of a short portion at the lower end, which is slightly enlarged, as will be seen upon reference to Fig. 3. A hollow piston-rod S is mounted in a stuffing box or gland T, carried by the upper end of the cylinder, said rod having formed or secured upon its inner lower end a head or plunger U, provided with a series of vertical openings or channels V, Figs. 2 and 3.

It will be noted upon reference to Fig. 2 that the lower central portion of the plunger-face is slightly cut out or depressed, forming a downwardly-projecting rim or skirt upon the plunger.

A cap or plate W, having a central opening X, is carried by the plunger and is so mounted thereon that it bears against the lower edge 20 of the depending skirt or rim, but is free to move therefrom when the piston is elevated. To maintain it in its place and to allow it to be moved away from the plunger, two screws Y are mounted in pockets formed in the 25 plunger, the end screws passing into the cap or plate and light springs Z being mounted between the heads of the screws and the lower inwardly-extending walls of the pockets.

A stem b is mounted in the hollow piston-rod, its lower end being tapered and coming 30 directly in line with opening X of the cap W. The upper end of the stem is threaded and engages with a thread formed internally upon the piston-rod, a suitable head or nut c being 35 carried by the stem at its upper end in order to facilitate adjustment thereof. A coil-spring d is placed around the piston-rod, bearing at one end against the plunger and at the other against the packing-gland, the spring 40 serving to normally hold the plunger and rod depressed.

A block e is secured to the upper end of the piston-rod and extends out sufficiently to project over a stud f, carried by the lever O, or, if desired, a projection may be formed 45 upon the block to engage the lever, this form being a mere reversal of parts. So, too, lever O may be dispensed with and the block, through a suitable arm O', Fig. 8, made to 50 act directly upon stops O², O³, carried by the valve-stem. A chain g connects the outer end of said lever to the block, the chain being of such length that the lever remains unaffected until the piston-rod and plunger or 55 head have nearly reached the upper limit of their movement, when the chain becomes taut, the lever elevated, and valve N opened. An eye h is secured to the upper end of the block, and a chain i connects said eye to the 60 hooked end of a rod j, which extends down from one end of a lever k, pivoted to a bracket secured to the ceiling or other suitable support. A weight l is placed upon the lever, between its fulcrum and said rod j. 65 To the opposite end of said lever k there is attached a short coiled spring m, from which

depends a rod n, connected at its lower end to chains o. Said chains pass around pulleys or sheaves mounted in pivoted brackets p and are connected to suitable arms q, secured 70 to the doors B.

As either of the doors B is opened the weight-ed end of lever k is elevated through the connections just described, and the upward movement of said end elevates block e, the piston-rods, and the piston-head or plunger U, the oil with which the cylinder R is filled passing down through the openings or channels V, forcing the plate or cap W away from the piston-head, allowing the oil to flow freely and 80 the piston to rise in the cylinder without being checked by the oil. It is manifest that the oil finds a ready outlet through the openings V out between the depending skirt and the cap and also through the opening X in the 85 cap. In other words, the cap-piece moves bodily away from the openings in the piston-head and permits a substantially unrestricted flow. By the upward movement of block e and the piston-rod spring d is compressed, 90 and as the block nears its limit of upward movement chain g becomes taut and valve-lever O is elevated, permitting the steam to pass through pipe J to the spraying-nozzles M. The steam-spray is deflected down upon 95 or over the fire, drawing in with it a certain quantity of air through openings D, the commingled steam and air serving effectually to prevent or consume any smoke which would otherwise arise. By adjusting the slide G in 100 or out the quantity of air and the direction of the spray may be regulated and determined, and when once adjusted it remains in its position and needs no further alteration upon the part of the furnace attendant. The lower 105 slide F serves to catch the drip which may come from the nozzles M and thus protect the casing or box E.

When the doors B are closed, the weight l depresses that end of the lever k which is connected to the arm j; but owing to the chain connection i the descent has no effect except to leave the spring d free to force the piston rod and head down.

The elevated position of the piston is shown 115 in dotted lines in the upper part of Fig. 2, and as the cap W rests or bears directly against the depending skirt of the piston-head the spring can force the plunger down only as fast as the oil can escape up through the central opening X, past the tapered end of rod b, and up through the openings V into the cylinder above the piston-head. By adjusting the rod b toward or from the cap or plate W the flow 120 of oil may be easily controlled and the rate 125 of descent of the piston-head determined.

It will be noted that during the first part of the downward movement of the plunger the valve-controlling lever O remains unaffected and the steam consequently continues to flow 130 through pipe J and discharge into the fire-chamber. This condition exists until the pis-

- ton-head reaches the enlarged portion of the cylinder, when the head *e* comes into engagement with the lever-stud *f*, and as the oil can now pass freely around the side of the piston-head the spring is no longer retarded and by a quick impulse or movement forces the piston rod and head to the lowest point, at the same time forcing the valve to its seat and shutting off the steam.
5. From the foregoing it will be seen that when the doors are opened the steam is turned on and that for a period after they are closed the steam continues to flow. As above stated, the period of after-flow may be regulated by the adjustment of the stem *b*.
10. Oil is the fluid preferably employed in the cylinder, though it is manifest that other fluids may be employed, if found desirable.
15. It will be noted in the construction of the cylinder and piston that the parts are readily accessible by simply removing the plug at the lower end, also that the valve or cap-piece *W* is of metal, insuring durability that is not present with the ordinary leather or rubber flap-valve.
20. Having thus described my invention, what I claim is—
1. In combination with the wall of a furnace, an air-inlet formed therein; and a two-part slide working in said opening, the upper member being provided with a deflecting member, which when drawn back serves to fit against the lower member and close the air-inlet, substantially as described.
  2. In combination with the wall of a furnace, an air-inlet formed therein; and a two-part slide mounted in said inlet one above the other, the upper member being formed with a forwardly-extending downwardly-inclined deflecting member, the lower member having its side walls beveled off, whereby when the upper slide is drawn back its deflecting member will fit down upon the beveled walls and close the inlet.
  3. In combination with the wall of a furnace, an air-inlet formed therein; slide *F* mounted in said inlet and having inclined faces *a* formed at the inner end thereof; and a slide *G* also mounted in said opening above said slide *F*, and having an inclined deflector-plate *H* designed when drawn back to fit against the faces *a* and to close the inlet.
  4. In combination with the wall of a furnace, an air-inlet formed therein; slide *F* mounted in said inlet and having inclined faces *a*, and rearwardly-extending handle *I*; and a slide *G* also mounted in said inlet above the slide *F*, having a deflector *H* and a handle *I*, said handles *I* being so formed as to engage the outer face of the furnace and prevent the slides from being forced inwardly out of the inlet.
  5. In a smoke-consumer, in combination with a furnace; an air-inlet formed therein; and a slide mounted in said opening and provided with the fire-chamber thereof; a steam-dis-
  - charge nozzle mounted in said inlet; a steam-supply pipe; a valve located in said pipe; a lever *O* connected to the valve-stem; a fuel-door; a lever *k* pivoted to a suitable support; a connection between one end of the lever and the door; a check-cylinder; a connection between the piston-rod of said cylinder and the opposite end of the lever *k*; a connection between lever *O* and said lever *k*; and a stop connected to the piston-rod designed to bear upon and depress the lever *O* when said rod nears its limit of downward movement.
  6. In a smoke-consumer, in combination with a furnace; air-inlets communicating with the fire-chamber thereof; steam-discharge nozzles mounted therein; lever *k* provided with a weight *l*; a rod *n* connected to one end thereof; doors *B*; chains *o* connecting said doors and rod *n*; rod *j* depending from the opposite end of lever *k*; a check-cylinder; a block connected to the upper end of the piston-rod thereof; a chain *i* connecting the lower end of rod *j* and said block; a valve controlling the supply of steam to the discharge-nozzles; a lever *O* connected to the valve-stem; a chain *g* connecting the lever and the block aforesaid; and a projection extending from the block out over the upper face of lever *O*.
  7. In combination with a cylinder having an enlarged chamber formed in its lower end; a piston-rod; a piston of such dimensions as to fit the smaller diameter of the cylinder; openings passing up through said piston; a cap-piece yieldingly supported upon the lower end of the piston and having an opening therethrough; means for restricting said opening; and a spring for forcing the piston down in the cylinder.
  8. In combination with a cylinder having an enlarged chamber formed in its lower end; a hollow piston-rod; a stem *b* mounted therein; a piston carried by the end of the rod and provided with openings *V* extending therethrough; a depending skirt formed upon the piston; a cap yieldably held against said skirt; and a spring for forcing the piston toward the enlarged chamber, substantially as described.
  9. In combination with a cylinder having an enlarged chamber formed at its lower end; a hollow piston-rod mounted therein; a stem *b* adjustably mounted therein; a piston carried by said rod and provided with openings *V* extending therethrough; a depending skirt formed upon the piston; a cap *W* having a central opening *X*; screws *Y* mounted in pockets formed in the piston extending through and engaging said cap; springs for holding the cap up to the skirt; and a spring *d* serving to force the piston down, substantially as described.
  10. In combination with the walls of a furnace; an air-inlet formed therein; and a slide mounted in said opening and provided with a deflecting member at its forward end de-

signed when drawn back to close the air-inlet, and when moved forward to serve to deflect the blast down onto the fire.

11. In a smoke-consumer, the combination of a steam-supply pipe; a valve mounted in said pipe; a check or controlling cylinder; a piston mounted in said cylinder and arranged to have a rapid movement near the completion of its stroke; and means intermediate

the piston and the valve for closing the valve quickly during the latter part of the movement of the piston.

In witness whereof I hereunto set my hand in the presence of two witnesses.

HENRY M. QUACKENBUSH.
